Inventor:

F. Merk

J. F. G. & Co. Attorneys

UNITED STATES PATENT OFFICE.

FRIEDRICH MERK, OF MUNICH, GERMANY.

INTERCHANGEABLE SET OF RELAYS FOR TELEPHONE PURPOSES.

Application filed September 20, 1927. Serial No. 220,725.

This invention relates to sets of relays in which the relays are mounted in a row on a bar, facility of interchanging the several sets of relays in using contact-connecting-bars for automatically producing or disconnecting the electric-connections being required. The invention relates particularly to the arrangement and construction of the contact-connection-bars. The bars must be simple, occupy little space, admit of a great number of contact-points and further ensure, in avoiding one sided pressure-action upon the set of relays, a good contact-pressure and secure contact-engagement. All soldering and contact points must be visible and accessible in the service.

According to the invention these conditions are fulfilled by arranging the connecting bar, consisting as usual of an apparatus-bar and of a frame-bar, on the rear of the set of relays, extending in the longitudinal direction of the same and carried out preferably in a double-row.

An embodiment of the invention is illustrated, by way of example, in the accompanying drawing in which:

Fig. 1 shows the improved relay-bar in elevation.

Fig. 2 shows in side elevation the relay-bar, fixed on the frame.

Fig. 3 shows in side-elevation, partly in section, a contact spring.

Fig. 4 shows in side elevation, partly in section, the pin of the frame on which the second bar is mounted.

Referring to Figs. 1 and 2, T is the relay-bar and R designates a number of relays fixed on said bar. The relays are arranged so that their contact-springs are situated on one side, the solder-connections of the contact-springs as well as of the relay-coils projecting at both sides of the bar T in rearward direction. The relays with the bar T form the set of relays proper.

A second bar S is fixed, according to the invention, to the bar T at a certain distance from the same and carries an apparatus-bar K¹ on which insulated contact-pins a¹, a² are mounted. The contact springs are constructed as shown in Fig. 3, as pieces of sheet-metal, bent at right angles and arranged in two rows. Each contact pin is arranged at the rear-end for contact-formation and at the other laterally projecting end (see Fig. 1) for solder-connection with

the relay and with any other apparatus which might be fixed on the bar T, for instance condensers C. With regard to the wire-connections, necessary for these purposes, the interval is provided between the apparatus fixed on the bar T or on the bar S.

The frame-bar K² consists of a set of contact-springs f, arranged also in a double row. The springs are insulated and held on a bar by means of cover-plates and screws. The springs of the two rows bear at the free end with preliminary tension against a rod G covered with an insulating tube. The rod G serves to maintain the contact-springs in the straight adjusted position when the set of relays is removed, in order that at the insertion of the set of relays a secure engagement of the contact pins with the contact springs be obtained. For the same reason the springs are further bent at the free end in inclined direction. The frame-bar with the springs and with the rod G is fixed as a whole by screws on the carrying frame of the set of relays.

The set of relays is fixed on the carrying frame by suspension on a rod D by means of a suspension bow H, adjustable rings r, r are fixed on the rod D, in order to accurately fix the suspending point. The set of relays is moved towards the rod D in inclined position, the suspension-bow H is then hooked over the rod and the set of relays pressed towards the frame. The contact pins of the set of relays engage between the contact-springs like knives and establish the contact-connection. For obtaining an accurate engagement of the contact pins with the contact-springs at the pressing on of the set of relays, the following special arrangement is made:

On the carrying frame a pin F is fixed and the bar S has a corresponding hole with which pin F must engage before the contact pins touch the contact-springs. A stop A on pin F limits the movement of the set of relays at the pressing on. A blade-spring B gripping around the bar S holds the set of relays, pushing up and dropping out of the set of relays being prevented by the pin F.

I claim:

1. An interchangeable set of relays for telephone purposes, comprising in combination with a carrying frame, a bar on which the relays are fixed, a contact bar spaced from and fixed to said relay bar, contact

pins fixed on said contact bar, a frame bar, and contact springs on said frame bar with which said contact pins come into touch when said relay bar with the relays is being suspended on the carrying frame.

2. In an interchangeable set of relays for telephone purposes as specified in claim 1 the arrangement of the contact pins of the

contact bar and of the contact bar and of the contact springs of the frame bar in two rows so that the insertion of the set of relays the two rows of contact pins of the contact bar spread the two rows of contact springs of the frame bar.

In testimony whereof I affix my signature.

FRIEDRICH MERK.
